UNITED STATES PATENT OFFICE.

GEORGE W. KENDALL AND CHARLES KRUSE, OF NEW YORK, N. Y.

CHECK REGISTERING AND PRINTING APPARATUS.

SPECIFICATION forming part of Letters Patent No. 286,019, dated October 2, 1883.

Application filed October 5, 1882. (No model.)

To all whom it may concern:

Be it known that we, GEORGE W. KENDALL and CHARLES KRUSE, both of the city, county, and State of New York, have invented new and useful Improvements in Check Printing and Registering Apparatus; and we do hereby declare that the following is a full and exact description thereof, reference being had to the accompanying drawings, and to the letters of reference marked thereon, making a part of this specification.

Our invention relates to a check printing and registering apparatus, and has for its object the simultaneous printing or marking of two separate strips of paper within an inclosing case and the subsequent automatic delivery from the case of one of the strips, from which the printed section may be detached to be used as a check, while the duplicate strip is retained within the case to serve as a complete and accurate register of the precise number and denomination of each check issued. This object is accomplished in our invention by means of a hinged and pivoted crank-lever or rotating arm arranged to vibrate upon the outside of the case over a fixed index-plate indicating the several numerals or other marks desired upon the checks, and which is coupled with an inner plate carrying type or marking devices corresponding to said marks, and with mechanism, as hereinafter described, for feeding forward the strips of paper and forcing the same for impression against the types or marking devices by means of a movement of the outer lever at the instant it is placed over the desired mark upon the index-plate.

In the accompanying drawings, Figure 1 is a top or plan view of our improved check printing and registering machine; Fig. 2, a central vertical section in line $x-x$ of Fig. 1, and Fig. 3 a transverse section in line $y-y$ of Fig. 2.

A represents the casing within which the printing and registering mechanism is inclosed, and which is designed to admit of being securely locked, so that said mechanism cannot be reached or the contents of the case removed, except by the party holding a key thereto.

B is a central annular plate fixed upon the outer upper face of the case.

F is a flat circular disk resting and rotating upon the annular disk B, to which it is partially confined by a semicircular overlapping flange, C, on the edge of the plate. The disk F is secured to a vertical tubular spindle, G, extending through the central aperture in the plate B, and through an opening in the casing, and whose lower end rests upon the bottom of the case, while its upper end finds its bearing in the encircling-aperture in the annular plate B. 55

A loose pin, H, is fitted within the tubular spindle G, to project upward therefrom through the top plate, F, and downwardly into a recess or socket in the bottom of the casing, as shown in Fig. 2. 65

The tubular spindle G and its inclosed pin H are carried through slots in a sliding frame composed of two bars, I I', fitted, respectively, 70 against the inner side of the top and bottom of the case, and which are connected together at the front by a transverse plate, J, and at the rear by a transverse spring, K, Fig. 2. 75

Between the spindle G and the rear end of the case two uprights, M M, are secured, to extend from the top to the bottom of the case on each side of the bars I I', between which they closely slide, and a bent lever, L, is pivoted at its angle upon a transverse rod, N, extending between the uprights, near to the upper bar, I'. (See Figs. 2 and 3.) 80

The horizontal arm of the lever L engages a notch in the pin H, the tubular spindle G being slotted to permit the same, and the vertical arm of the lever engages a recess in the lower bar, I, at such a point as that when the bars I I' are forced forward by the spring K the lever shall operate to hold up the loose pin H, so that its upper end shall project up well above the plate F, as shown in Fig. 2, 85 while pressure exerted upon said pin shall, by moving the lever L, cause its lower arm to draw back the bars I I' rearward, and thereby compress the spring K. 90

A sleeve, O, is fitted and secured upon the tubular spindle G, below the slot therein, and is provided with a segmental plate, P, extending horizontally therefrom, and whose outer 95 100

curved edge, R, describes the arc of a circle having the axis of the spindle G as its center. This edge is widened sufficiently to carry two rows of type, *a a'*, one above the other, (see 5 Fig. 2,) and the one an exact duplicate of the other, the types being separated from each other by uniform intervals. The radius of the arc is of such length as to bring the type into close proximity to the movable plate J when 10 in line at right angles thereto, (see at 5, Fig. 3,) so that when the bars I I' are drawn rearwardly by the movement of the lever L the plate J is brought as a platen into contact with the type.

15 An inking-ribbon, S, led over rollers T T', is made to pass over the face of the type, between the type and platen-plate J. Two separate strips of paper, V V', (see Fig. 2,) are wound side by side upon a drum or roller, W, 20 which is mounted in one end of the case A, (see Fig. 3,) and are led from said roller in between the platen J and the inking-ribbon S, one opposite one row of type, *a*, and the other opposite the second row, *a'*, and after passing 25 the plate J one of them, V, is led out from the case through a slit in the face thereof, while the other, V', is carried to a take-up roller, W', within the case at its opposite end.

To feed forward the endless inking-ribbon 30 S and the strips of paper V V', a friction-roller, T'', is placed in such close proximity to and parallel with that one of the rollers T', over which the ribbon is carried lastly before reaching the platen J, as to exert a pressure 35 upon said roller J'. The strips V V', led between said friction-roller T'' and ribbon-roller T', in connection with the ribbon S, are subjected to this pressure, so that a revolution of the rollers shall carry the paper and ribbon 40 forward. The rollers are rotated intermittently by means of an angular lever, *c*, pivoted to the bottom of the case, so that its shorter inner arm shall engage a notch in the side of the sliding bar I, and its longer outer arm shall 45 extend to within a short distance of the roller T'. The lower end of this roller is fitted with ratchet-teeth on its circumference, and a hooked pawl, *d*, is pivoted to the end of the outer arm of the lever *c*, and actuated by a 50 spring, so as to engage the ratchet. When the sliding bar I is moved rearward by the action of the lever L and pin H to draw the platen-plate J against the type, the lever *c* will be moved so as to throw its pawl forward to engage one of the ratchet-teeth. So soon as the 55 bar I is released and forced forward by its spring K its forward movement, operating to throw the lever *c* back, will cause the pawl *d* to draw upon the ratchet, and so rotate the 60 roller T' to an extent measured by the movement of the lever, and which is graduated so as to be equal to the interval desired between the characters when imprinted on the strips.

The pin H is depressed and the platen-bars 65 I I' consequently moved to produce an impression upon the paper, and a subsequent

movement of the latter, by means of a lever, Y, whose inner end is pivoted between lugs *e e*, projecting upward from the outer face of the annular rotating disk F, and which projects thence over the head of the pin H, and terminates over a segmental plate, D, whose arc corresponds to that of the segmental type or die carrier R beneath. The head of the pin H enters a recess upon the under side of the 70 lever Y, and serves as a pivotal center upon which the lever may rotate, carrying with it the disk F, spindle G, and type-carrier R. The plate D is formed with a series of notches, 75 *f f*, equal in number to the number of duplicate types on the type-carrier R, and which are separated by uniform intervals corresponding exactly with the intervals between said types. These notches are designated by characters marked upon the edge of the plate corresponding to the characters on the types, their consecutive order being, however, reversed, as is illustrated in Figs. 1 and 3.

In the operation of the machine the lever Y is turned until its outer end is in register with 90 the notch on the plate D, which corresponds with the numeral or other character desired upon the check. The rotation of the lever Y carries with it the disk F, the tubular spindle G, and the type-bearing arm P, which, being 95 all connected together, turn about and upon the central loose pin, H, as an axis, and the types are so disposed, as herein described and illustrated, as that when the lever Y is turned to the given notch upon the plate D 100 the duplicate types corresponding to the character by which the notch is designated are brought into line with the platen-plate J. If, now, the end of the lever be pushed down into the notch, its pressure upon the pin H will cause said pin to force down the horizontal arm of the lever L, and thereby cause the lever to draw the bar I rearward, and thereby bring the platen J against the strips 105 of paper V V' and force them upon the inking-ribbon against the type, brought into position by the rotation of the lever Y, as above described. The two strips V V' will be thus both printed simultaneously with the same 110 number or letter. So soon as the lever Y is lifted from the notch in the plate D and the pin H is relieved of its pressure, the spring K, which was compressed by the rearward movement of the bars I I', will react, and, forcing the bars and platen back, will actuate the lever *c*, so as to cause its pawl *d* to move the feed-rollers T' T'', and thereby carry forward 115 the strips of paper V V' into position to receive a second impression. As the strips of paper are thus automatically fed forward after each movement and stroke of the lever Y, one of the strips, V, so soon as it has passed the impression-point and received its imprint, is led 120 out from the machine and the projecting end, bearing the required imprint, may be torn off 125 for use as a check-ticket. The second duplicate strip, V', however, is led to the take-up 130

roller W and wound thereon by the operation of a spring or other suitable mechanism, and remains as a complete record in duplicate of every check-ticket taken from the machine.

5 To facilitate the manipulation of the lever Y in printing and working off the checks, the rear end of the lever may be extended in the form of a pointer, Y', to sweep over a segmental plate, E, upon which the type characters 10 are designated in the same order of arrangement and intervals as are the types, each character being in position, so that when the pointer is over it the other end of the lever may drop into the appropriate notch in the plate D.

15 It is evident that the types may be so constructed as to emboss or even cut out the appropriate characters on the paper pressed against them by the platen J. In such case the inking-ribbon S is dispensed with, and the 20 strips of paper, instead of being placed and led forward side by side, one above the other, may be superimposed one upon the other, so that both thicknesses thereof will be simultaneously embossed or perforated by the same 25 type.

We contemplate also combining a cutting device with the printing mechanism, so that the checks or tickets to be delivered from the machine shall be severed from the strip as they are 30 issued, leaving the record-strip only in continuous form, and shall make these improvements the subject-matter of separate applications for Letters Patent.

Two or more duplicate record-strips, V', may 35 be imprinted instead of one, as described, where such are needed, in connection with the issue of the checks or tickets, and the position and relative arrangement of the several parts of the machine may be changed, so as 40 to produce an issue of the checks from the top instead of the side thereof.

We claim as our invention—

1. The combination, in a ticket printing and recording machine with a rotating or reciprocating plate or rack, R, carrying suitable type or dies, a pressure-platen, J, adapted to move toward the same, and a case, A, inclosing the whole, of a single drum or supply-roller, W, and two or more separate strips, V 50 V', wound thereon and adapted to be led conjointly therefrom within the case between the types and platen to receive simultaneously an impression from the type or dies by means of

pressure from the platen, and to be thence led separately, the one out of the case for division and use in the form of checks or tickets, and the other to a compartment within the case to serve as duplicate register of the first, all substantially in the manner and for the purpose herein set forth. 55

2. In a ticket-printing machine, the rotating spindle G, segmental type or die carrier R, lever Y, and index-plate D or E, combined with each other and with a pressure plate or platen, J, substantially in the manner and for 60 the purpose herein set forth.

3. The combination, with a rotating tubular spindle, G, a segmental type or die carrier, R, secured thereto, a lever, Y, hinged to its outer end, an index-plate, D or E, over which 70 the lever may traverse, and a movable pressure plate or platen, J, opposite the type or die carrier, of a loose pin, H, within the spindle, upon which the lever Y may rest, a spring-actuated sliding bar, I, carrying the pressure 75 plate or platen J, and a bent lever, L, pivoted at its elbow to engage with one arm the pin H and with its other arm the bar I, all substantially in the manner and for the purpose herein set forth. 80

4. The combination, with the type or die carrier R, pressure plate or platen J, actuating-arm I, lever L, loose pin H, and lever Y, of the pawl-lever c, pawl d, ratchet-roller T', and friction-roller T'', said rollers being adapted by their rotation to feed forward two or more strips of paper, V V', between the platen J and type or die carrier R, all substantially in the manner and for the purpose herein set forth. 85

5. The case A, type or die carrier R, tubular spindle G, lever Y, index-plate D, loose pin H, lever L, actuating-arm I, platen J, lever c, pawl d, ratchet-roller T', friction and guide roller T'', inking-strip S, supply-roller 90 W, and check-strips V V', all combined and operating together substantially in the manner and for the purpose herein set forth.

In testimony whereof we have signed our names to this specification in the presence of 100 two subscribing witnesses.
